(No Model.)

M. GARLAND.
SPROCKET WHEEL AND CABLE.

No. 366,472.

Patented July 12, 1887.

WITNESSES:

W. J. Graham
A. M. Williamson

INVENTOR
Michael Garland

BY
J. N. McTigue

ATTORNEY

UNITED STATES PATENT OFFICE.

MICHAEL GARLAND, OF BAY CITY, MICHIGAN.

SPROCKET WHEEL AND CABLE.

SPECIFICATION forming part of Letters Patent No. 366,472, dated July 12, 1887.

Application filed March 3, 1887. Serial No. 229,513. (No model.)

To all whom it may concern:

Be it known that I, MICHAEL GARLAND, of Bay City, in the county of Bay and State of Michigan, have invented a new and useful Sprocket Wheel and Cable; and I do hereby declare that the following is a full, clear, and exact description thereof, reference being had to the accompanying drawings, making part of this application.

Previous to my invention a great variety of contrivances for the transmission of power and motion and involving the use of some sort of wheels or pulleys having combined with them some sort of drive-belt have been used, divisible into two general types—viz., that class in which the engagement between the peripheries of the wheels and the endless band or belt has been by frictional contact only, and that kind in which a positive interlocking device has served to engage the wheels with the endless band or chain belt.

My invention relates to that type of transmitter in which the endless traveling band or belt effects a positive engagement with the wheels over or partially around which it passes; and it consists, essentially, in the combination, with wheels having their peripheries circumferentially grooved, and having the radial flanges at either side of the circumferential groove formed with teeth or sprockets, of a wire or other rope or cable adapted to run in said groove, and provided with devices (made fast thereon) adapted to engage positively with the depressions or spaces between the teeth or sprockets of the wheel's flanges, all as will be hereinafter more fully explained, and as will be more particularly pointed out and explicitly defined in the claim of this specification.

To enable those skilled in the art to which my invention relates to understand and practice the same, I will now proceed to more fully describe it, referring by letters to the accompanying drawings, which form part of this specification, and in which I have shown my invention carried out in those forms in which I have so far successfully practiced it, and which are about the best forms now known to me.

In the drawings, Figure 1 is a side view or elevation of a pair of wheels and an endless

drive rope or band belted on them, all according to my invention. Fig. 2 is a top or edge view of the same wheels seen at Fig. 1, and showing part of a similar drive cable, but out of connection therewith, the rope being shown, however, as provided with several different species of wheel-engaging and other devices, to be hereinafter more fully described. Fig. 3 is a view looking sidewise at the rope and the several attachments thereto that are shown in top view at Fig. 2. Fig. 4 is a partial top view (on a smaller scale) of a duplex or double-run drive-belt with attachments adapted to the purposes of a conveyer-machine. Fig. 5 is a cross-sectional view of the same, taken at the line *x x* of Fig. 4. Fig. 6 is a detail cross-section at the line *y y* of Fig. 1. Fig. 7 is a detail cross-section at the line *z z* of Fig. 3. Fig. 8 shows a form of cable device adapted to carry an elevator-bucket.

In the several figures the same part will be found designated by the same letter of reference.

In Fig. 1, A and A' represent two wheels or pulleys mounted upon suitable shafts, A⁴, and being banded together or belted by a wire rope or cable, A⁵, upon which are arranged and secured at equal distances apart a series of transversely-arranged bars or devices, A⁶, of a peculiar construction, and for a purpose to be presently explained.

A and A' are duplicates, so that a description of the structure of one, which I will now give, will answer for both.

The wheel A, as will be clearly seen by reference to Figs. 1 and 2, is made in the form of a simple rope wheel or sheave, having its periphery circumferentially grooved for the accommodation of the wire cable or rope A⁵, but having the radially-arranged flanges, between which lies the peripheral groove, notched or cut out, so as to form two series of teeth or sprockets, A², the said teeth of each flange being arranged exactly in line (axially of the wheel) with those of the other flange. In other words, what would otherwise be the two radial flanges of an ordinary peripherally-grooved rope-wheel are made to constitute two toothed disks or sprocket-wheels, as clearly illustrated.

The transversely-arranged bars A⁶, before

mentioned, are made, preferably, each in two parts, securely embracing the rope or cable A⁵ within semi-cylindrical recesses formed in the parts of the device A⁶, within which the said 5 rope or cable is securely clamped by the bolts or screws B, by which the two parts of each of the devices A⁶ are held together, and these devices A⁶ are arranged equidistant and at a distance apart equal to the distance between 10 the spaces between the teeth or sprockets A² of the wheels. In other words, these devices A⁶ are arranged at such distances apart as that in passing around or over the wheels they will match or correspond with the pitch 15 of the sprockets or teeth of said wheels, so as to run in perfect gear or engagement with the spaces between the roots of said sprockets, all as clearly illustrated at Fig. 1.

By preference the duplicate clamp-like devices A⁶ have their semi-cylindrical recesses provided with semi-cylindrical bushings, of some suitably soft metal or other material, for the purpose of effecting a perfectly-reliable union (by the enforcement together of its parts 25 by the action of the screw-bolts B) between said devices A⁶ and the wire or other rope or cable A⁵.

Those surfaces or portions of the device A⁶ which are arranged to run in mesh or in engagement with the sprocket-wheels formed by cutting the peripheral flanges of the sheaves into teeth A², as shown, are shaped so as to match with the contour of the spaces between the said teeth. This conformation of the device A⁶ with the toothed flanges of the wheels is clearly shown at Fig. 1.

Now, it will be understood, of course, that in a power and motion transmitting contrivance composed, as shown in Fig. 1, of a pair 40 of wheels having their peripheries grooved to seat a rope or cable, A⁵, and also having the radial flanges formed into sprocket-wheels with teeth A², with which the devices A⁶ (secured to the rope) engage, as shown, a 45 positive interlock or engagement is effected between the said wheels and the said drive rope or band, while at the same time the band proper is composed of a simple cable or rope, cylindrical in cross-section, and the 50 peripheries of the wheels provide simple grooved bearing-faces for the reception and retention laterally of the drive-rope, and it will be seen that in such a contrivance a greater or less number of the engaging devices A⁶ 55 may be employed to run in mesh with the sprocketed flanges of the rope-wheel.

Of course the distance between the engaging devices A⁶ of the cable may be varied by loosening, slightly shifting, and retightening 60 the parts of said devices whenever, by reason of any stretching of the cable or rope, the predetermined or original spaces between said engaging devices may be found to vary to any extent from the true pitch of the sprocketed 65 flanges of the rope-wheels.

The conformation or contour of the teeth A², and consequently of the spaces between

them, as well as the shape of the engaging devices A⁶, may of course be varied from what I have shown in the drawings without changing the principle of construction or mode of operation of the contrivance, so long as these parts are of any proper shape to properly engage or mesh together, and some other detail construction of the engaging devices A⁶, by means of which they might be either permanently or adjustably secured to the rope A⁵, may be adopted in place of those I have shown in the drawings without departing from the nature of my invention. When desirable, the 80 rope-grooves of the wheels may be lined with vulcanized rubber.

In case it may be desirable or expedient, the transversely-arranged engaging devices of the rope or cable may be either so differently constructed from those seen at A⁶, or may be so supplemented with other devices, as to render the traveling cable and its attachments capable of performing not only the transmission of motion and power from one wheel-and-shaft 90 to another, but also performing any of the usual functions or purposes of conveyer chains or belts.

At Fig. 2 I have shown the rope or cable A⁵ provided with several forms of transversely-arranged and securely-clamped devices that are adapted not only to engage with the toothed flanges of the rope-wheels there shown, but also perform, respectively, the usual functions or offices necessary to conveyer-machines of 100 different species. For instance, at A⁷ I have shown a rope attachment or device designed to perform the function of grabbing and hauling a log, after the usual fashion in "log-haul-up" machines, while at A⁸ I have shown a 105 device similar to the usual scraper or "flight" used in conveying-machines for moving sawdust, coal, clay, &c. The device shown at A⁹ is another form of a mere engaging device for engagement with the sprocket-teeth of the 110 wheels, while at A¹⁰ is another form of device for the same purpose.

Of course in the application of my invention to the various forms of conveyer or carrier machines—such as coal and sawdust conveying contrivances, log-haulers, &c.—the necessary and peculiarly-constructed flights or devices for such purposes, securely attached in the proper manner to the wire cable or rope A⁵, may be interspersed with devices—such as 120 seen at A⁶—for engagement only with the teeth of the wheels which either drive the cable or are driven by it.

At Fig. 8, P is a bucket for carrying flour, grain, &c.

It will be readily understood that the various applications of flights and log-hauling and other attachments for different kinds of conveying-machines, or for cable drive-chain purposes, may be almost endless within the 130 scope of my invention.

In lieu of a single drive rope or cable, A⁵, adapted to run in engagement with a single pair of wheels, and provided with some sort

of transversely-arranged devices which engage with the teeth A^2 thereof, a duplex or double-run driving and carrier contrivance may be made, after the fashion illustrated at Figs. 4 and 5, by the use, as there shown, of two separate ropes or cables, each running over a separate set of sheaves or wheels, and transversely-arranged devices—such as seen at A^{11} or A^{12} —securely clamped at each of their ends 10 to one of the cables and adapted to engage with the toothed radial flanges of wheels somewhat similar to those seen at Figs. 1 and 2. If it be thought desirable or expedient in the construction of such a double-run or duplex 15 drive mechanism and carrier mechanism, the wheels in such contrivance may be made with only one peripheral flange to each wheel, suitably toothed to engage with all of the devices A^{11} or A^{12} near one end only of each. 20 Of course it will be understood, without further description here, that in either the use of a single run or double run of cables, such as shown and described, provided with suitable attachments for positive engagement with the 25 toothed flanges of the peripherally-grooved wheels, almost any and every sort of known flight or carrier attachment may be employed

with the same facility as in the case of carrier bands or chains of the constructions heretofore known and used.

What I therefore claim as of my invention, and desire to secure by Letters Patent, as a novel contrivance for either the transmission of power and motion, or for both transmitting power and motion and performing any of the 30 known offices of conveying-machines or carrier-chains, is—

The combination, with a rope or cable provided with a series of transversely-arranged sprocket-like or engaging devices which project laterally of said rope, of wheels each of which has a peripheral groove for the accommodation of said rope, and the flanges of which are toothed or notched to effect a positive engagement with the laterally-projecting portions of said engaging devices, all in substantially the manner hereinbefore set forth.

In witness whereof I have hereunto set my hand this 24th day of February, 1887.

MICHAEL GARLAND.

In presence of—

W. J. McCORMICK,
C. E. ESTABROOKS.
